UNITED STATES PATENT OFFICE.

AUGUST BRUN, OF CHICAGO, ILLINOIS.

PROPELLING DEVICE FOR BOATS.

Application filed August 5, 1926. Serial No. 127,302.

The principal object of the invention is to provide an improved device for propelling boats through water. By employment of the propeller of the invention, all of the power of the associated motor is efficiently applied against the water, the water is forced rearwardly without any relative slippage such as is had with ordinary screw propellers, and the boat may be reversed and turned abruptly in a very small area.

Other objects and advantages of the invention will be evident to those skilled in the art upon a full understanding of the construction, arrangement and operation of the parts incorporated in the propeller.

One embodiment of the invention is presented herein for the purpose of exemplification, but it will of course be understood that the invention is susceptible of embodiment in other structurally modified forms coming equally within the comprehensive scope of the appended claims.

In the drawing:

Fig. 1 is a side view of the stern of a boat equipped with the propeller of the invention;

Fig. 2 is a rear view of the stern of the same boat;

Fig. 3 is a side view of the propeller;

Fig. 4 is a rear view of the propeller with the blade in its uppermost position;

Fig. 5 is a similar view with the blade in its lowermost position;

Fig. 6 is a horizontal section through one of the two side reversing propellers, taken on the line 6—6 of Fig. 1;

Fig. 7 is a vertical section through the same reversing propeller with the blade in its closed position; and

Fig. 8 is a similar section with the blade in its open position.

It will be observed in the drawing that the propelling device includes three units—a propeller 10 arranged beneath the stern of the boat for imparting forward movement, and two auxiliary reversing propellers 11 arranged at opposite sides of the boat near the stern for imparting rearward movement.

The propeller 10 is set into an aperture 12 in the rear end of the keel 13, and operates from a point just forwardly of the rudder 14. The propeller 10 includes a stationary housing 15 and a movable blade 16. The housing 15 is closed at its forward end, and is provided with a short upper wall 17 and a long lower wall 18 in rearwardly diverging relation to the wall 17. The upper and lower walls 17

and 18 preferably increase in width toward the rear ends thereof. The blade 16 is pivoted on a horizontal axis 19 in the forward closed end of the housing, and extends rearwardly between the upper and lower walls 17 and 18, terminating at a point rearwardly of the upper wall 17 and substantially even with the lower wall 18.

The blade 16 is provided along the side edges thereof with downwardly extending flanges 19, and the lower wall 18 of the housing beneath the blade is likewise provided along the side edges thereof with downwardly extending flanges 20 which fit closely with the flanges 19 but permit the latter to slide freely relative thereto. The flanges 20 are in turn provided along the lower edges thereof with flanges 21 which extend upwardly along the outer sides of the flanges 19 of the blade and connect with the upper wall 17 of the housing, thus constituting side closures for the wedge-shaped space between the upper and lower walls 17 and 18 in which the blade 16 oscillates.

The blade 16 is moved upwardly and downwardly about the axis 19 by means of a link 22 which is pivoted at its lower end to a laterally elongated bracket 23 secured to the top of the blade rearwardly of the upper wall 17 of the housing. The link 22 is pivoted at its upper end to a cross-head 24 which slides upwardly and downwardly in a forwardly inclined guideway 25 in the keel 13 and is reciprocated by a rod 26 which extends at the same inclination through an aperture in the stern at the upper end of the guideway. The rod 26 is connected in any suitable manner with the motor mounted within the hull.

It will be understood from the foregoing that when the rod 26 is reciprocated the blade 16 oscillates upwardly and downwardly in unison therewith, and that the water in which the propeller is submerged is forced rearwardly, first from the tapering space between the blade 16 and the lower wall 18 and then from the tapering space between the blade 16 and the upper wall 17. All of the water pocketed in such spaces must necessarily leave the same rearwardly, as the flanges along the side edges of the blade and those along the side edges of the upper and lower walls effectively preclude the water from escaping along the sides. The stroke of the operating rod 26 is preferably adjusted in such a way as to prevent the blade 16 from coming into actual contact with either

the upper or lower walls 17 and 18 of the housing.

It will of course be appreciated that the propeller 10 is not capable of imparting any rearward movement to the boat, and the auxiliary reversing propellers 11 are consequently provided for that purpose. The propellers 11 are mounted in the sides of the hull, and are, when not in use, disposed flush with such sides 27.

Each of the reversing propellers 11 consists of a blade 28 which is pivoted at its rear end on a substantially vertical axis 29. The blade 28 is provided along its upper and lower edges with perpendicularly extending flanges 30 which increase in width toward the front end of the blade and slide in correspondingly shaped slots 31 formed in a housing 32 which is secured to the inner side of the hull opposite the blade 28 in such a way as to render the hull waterproof at that point. The housing 32 is provided, intermediate the slots 31 with a wall 33 which is parallel to and substantially flush with the side 27 of the hull. When the reversing propellers 11 are not in use, the blade 28 of each is disposed flush with the side of the hull in close relation to the wall 33 of the housing, but when such propellers are being used, the blade 28 of each oscillates outwardly and inwardly, causing the water entering the wedge-shaped space between the blade 28 and the wall 32 when the blade is in its outermost position to be forced forwardly, thus imparting rearward movement to the boat. The blade 28 is oscillated toward and away from the wall 33 in the side 27 of the hull by means of a rod 34 which is pivoted at its outer end to a bracket 35, secured to the inner side of the blade. The rod 34 extends into the hull through a closely fitting aperture in a cylinder 36 which is rotatably supported between two closely fitting concave bearing brackets 37 secured to the inside of the wall 33 of the housing 32. The rod 34 is connected in any suitable manner within the hull to the motor.

The reversing propellers 11, in addition to

being used together to impart rearward movement to the boat, may be used separately to warp the stern of the boat to one side or the other.

I claim:

1. A propelling device for boats, comprising a stationary blade, a movable blade pivoted substantially in the plane of the stationary blade for oscillation toward and away from the same, flanges extending perpendicularly from the edges of each of the blades substantially in contiguity with each other, flanges extending reversely from the edges of the flanges on one of the blades about the flanges on the other of the blades, and means for effecting oscillation of the movable blade.

2. A propelling device for boats, comprising a stationary blade of rearwardly increasing width, a movable blade of corresponding shape pivoted substantially in the plane of the stationary blade for oscillation toward and away from the same, flanges extending perpendicularly from the edges of each of the blades substantially in contiguity with each other, flanges extending reversely from the edges of the flanges on one of the blades about the flanges on the other of the blades, and means for effecting oscillation of the movable blade.

3. A propelling device for boats, comprising a housing positioned beneath the stern of the boat and provided with a short upper wall and a long lower wall in rearwardly diverging relation to the upper wall, a long blade pivoted adjacent the forward end of the housing on a horizontal axis for oscillation between the upper and lower walls, a laterally elongated bearing bracket secured to the top of the blade rearwardly of the upper wall, a link pivoted to the bracket, a guideway extending upwardly and forwardly from the housing, a cross-head slidably mounted in the guideway and pivoted to the link, and a reciprocating rod connected with the cross-head.

In testimony whereof I have hereunto subscribed my name.

AUGUST BRUN.
